UNITED STATES PATENT OFFICE

HENRY HAROLD HOLMES, OF LEICESTER, ENGLAND, ASSIGNOR TO WILDT & COMPANY, LIMITED, OF LEICESTER, ENGLAND, A BRITISH COMPANY

KNITTING MACHINE

Application filed February 28, 1928, Serial No. 257,621, and in Great Britain April 5, 1927.

This invention consists in improvements in or relating to knitting machines, and has for its object to provide improved means for producing patterns in the knitted fabric with the aid of a designer wheel, drum or like rotary device. Hereinafter, for brevity, such a wheel, drum or the like will be referred to inclusively by the term "designer wheel or wheel".

The type of designer wheel to which the present invention relates is that comprising a plurality of movable or removable bits which are intended operatively to engage the needles or needle jacks, which are so disposed in the wheel that the length of each bit will be substantially radial with respect to the associated needle cylinder when in a position to co-operate with a needle or needle jack therein, and which are each provided or formed with one or more projections or recesses. The position, in the lengths of the bits, of such projections or recesses varies, as between one bit and another, in accordance with the pattern to be produced. Co-operating with the bits are selector elements, such as movable cams, one allocated to each of the several positions in the lengths of the bits at which a projection or recess may occur. The purpose of this combination is to select certain bits which, in their turn, will effect a selective action on the needles (by raising or by failing to raise certain of them or by raising some of them higher than others), thus causing the stitch made by a selected needle to differ from that made by an unselected needle. For instance, the difference may occur in the nature of the stitch or the kind or colour of the yarn or yarns taken by the needles.

Hitherto, it has been proposed, through the agency of the selector elements, to slide the bits lengthwise (i. e. radially of a disc-like designer wheel) into and out from the path of the needle butts and thereby to select and raise certain of the needles in accordance with the pattern to be produced.

The present invention comprises the combination of a designer wheel and co-operating selector elements therefor having the bits pivotally mounted in the wheel and each

selector element movable into and out from a position in which it can operatively engage its appropriate bits and swing them about their pivots. The purpose of thus swinging the bits is to cause them, by their movements, to effect the requisite and desired selective action on the needles. 55

Preferably, when the bits are formed with projections, the latter on all the bits are of one and the same height; that is to say, they all extend the same depth from that edge of the bit which will be adjacent the selector element. 60

The invention also includes other features of novelty which will be more fully understood from the following description of one preferred example of the invention, read in conjunction with the accompanying drawings, in which— 65

Figure 1 is a plan looking from above, of the parts of the patterning mechanism necessary for the understanding of the present invention; 70

Figure 2 is an elevation of the parts shown in Figure 1; 75

Figure 3 is a detailed view showing, in side elevation, two adjacent selector elements looking in the opposite direction to that of Figure 2;

Figure 4 is a detail showing the formation of the ends of the selector levers; 80

Figure 5 is a section on the line 5—5 of Figure 1 in a plane normal to the surface of the wheel and is a true section with the exception, for the sake of clearness, of the illustration of the wheel trick itself, and 85

Figure 6 is a development of the interior of the cam-box in the region of the designer wheel showing the relative positions of the several cams therein. 90

Like reference numerals indicate like parts in all the figures of the drawings.

In the example illustrated, the designer wheel 10 is arranged, as in the case of known designer wheels, so that its axis is inclined with respect to the lengths of the needles contained in the needle cylinder 11. If it is applied to that type of machine in which the cam-box revolves around the needle cylinder, the designer wheel is to be understood 95 100

as supported from the cam-box or a part associated therewith so as to revolve in company with the cam-box around the needle cylinder. In doing so, it is also revolved about its own axis. If, on the other hand, the invention is to be applied to a rotating cylinder type of machine, the designer wheel will be held fixed in space and will be rotated about its own inclined axis. The speed of rotation of the designer wheel relatively to the needle cylinder is such that the bits in the designer wheel will register in succession with the tricks in the needle cylinder. The rotation of the designer wheel about its own axis may be effected by any form of drive; for example, by means of a gear wheel or a ring of teeth 12 on the designer wheel adapted and intended to mesh with a ring gear on the needle cylinder. For this purpose, the cylinder ribs may be formed to provide gear teeth by shaping them or the teeth may be supplied on a separate ring gear secured to the cylinder. As a further alternative, the designer wheel may be rotated by engagement 25 of the needle butts or the butts on needle jacks with the tricks of the designer wheel.

The wheel 10 is in the form of a disc-like member having radially-formed tricks at the inner end of which there is an annular rib 13. In each trick there is a bit 14 having a hooked inner extremity to pass over and to pivot on the rib 13, and a cover ring 15, secured to a boss 16 which is coaxial with and is itself secured to the wheel disc 10, serves to hold 35 the bits in position.

The bits are formed with projections 17 which extend upwardly from them when they are in position on the wheel, and the position of the butts 17 in the lengths of the bits will 40 vary as between one bit and another (for instance, see the two bits illustrated in Figure 2) in accordance with the pattern to be produced.

Co-operating with the bits is a plurality of selector devices, each comprising a number of levers 20 arranged to extend at one end over the designer wheel substantially at right-angles to a diameter thereof. In the actual construction illustrated, the levers are in the 45 form of bell-crank levers mounted to rock on a spindle 21 which is carried in a fixed frame 22 carried on an annular plate 23 that revolves in company with the cam-box. One arm of each bell-crank lever lies over a pattern drum 24 in which projecting cam-like members 25 can be secured. In the end of each bell-crank lever is a set-screw 26 by which adjustment of the lever in respect of the cam-like elements 25 can be made. The 50 other end of the bell-crank lever 20 extends over the pattern wheel as shown, and these ends of all the levers are arranged side-by-side, in the length of the aforesaid diameter, so that together they virtually lie over an 55 annular width of the wheel corresponding to

the major portion of the length of a bit. There may be any number of such levers, and in the example illustrated, there are twelve of them. The bits will have projections on them which correspond in position, radially of the wheel, to any one or more of the levers. 60

The cam-like elements 25 will be arranged in circular zones around the drum 24 there being as many such zones as there are levers 21. 65

In order operatively to engage a lever 20 with a bit 14, there is interposed between each lever and its bit a sliding foot 27 of the shape shown in Figure 3. The foot is formed with an upwardly-extending shank portion, and all the shank portions are received in a comb or slotted guide member 28, which latter is carried at the end of a cranked support 29 mounted on the frame 22. The feet 27 are all normally held upwardly, that is, away from the designer wheel, each by a spring 30 anchored at one end to the foot 27 and at the other end to a bracket 31 secured to a side of the comb or guide member 28. 75

As will be seen from an examination of Figures 1 and 3, the shanks of the feet 27 are arranged alternately throughout the series of feet on opposite sides of the centre-line of the slot or comb 28. The co-operating ends of the levers 21 are alternately long and short. The extremity of the short arm is formed as shown at 200 in Figure 4, and that of the long arms as at 201 in Figure 4, from which it will be seen that the latter is cranked so as to pass over the edge of the comb or guide member 28 towards the far side thereof to engage with its appropriate shank. The guide or comb member 28 is formed with slots to receive the ends, such as 200 and 201, of the levers 20 so as to guide and steady them in their movements. 90

It will be seen, therefore, that when a cam 25 on the drum 24 engages the end of a lever 20, the latter will be rocked about the spindle 21 so that its other extremity is depressed to move the foot 27 into a position at which it will engage the appropriate projections 17 on the bits 14; and all the bits which have projections coming within the influence of the particular foot 27 that has been depressed will themselves be depressed seriatim as the designer wheel 10 revolves on its axis. 105

In order to produce a change in the pattern, it is necessary that the drum 24 be racked round to bring, at required intervals, a different set of cams, such as 25, into operation. For this purpose, there is secured to the spindle of the drum a ratchet wheel 40. A clawker 41 is pivotally carried at the end of one arm of a bell-crank 42, and the latter is pivotally mounted about an axis 43 in the frame 22. At the other end of the bell-crank 42, there is an anti-friction wheel 44 which traverses a rising cam 45 mounted 110

on a stationary part of the machine. Cams, such as 45, may be disposed at intervals around the periphery of the needle cylinder in accordance with the number of steps that it is desired to rack the drum 24 during each revolution of the cam-box. Alternatively, a cam, or cams, such as 45, may be carried by a part that is movable into and out of the path of the wheel 44 at desired times. The insertion of each such cam into the path of the wheel 44 will be controlled by mechanism well understood in this class of machinery. It will be observed, however, that whenever the roller 44 rides over a cam, such as 45, the bell-crank 42 will be rocked on its pivot and the clawker 41 will rack the drum around one step and will be retracted into engagement with the next tooth in succession on the ratchet wheel 40 when the wheel 44 is lifted by the cam 45. A spring 46 normally holds the clawker 41 pressed towards the ratchet wheel 40 and another spring 47 normally holds the bell-crank lever so that the wheel 44 is pressed towards the annular member 23 and the cam, such as 45. Each racked movement of the drum 40 may serve to bring a different cam or different set of cams 25 into operative position in relation to the bell-cranks 20, or more than one racked step may be needed for this purpose according to the requirements of the design. From the description of the above parts, however, it will be clear that under the control of the drum 24 and the intermediate bell-cranks 20 and feet 27, the bits 14 can be selected in accordance with a predetermined pattern due to the fact that the bell-cranks 20 are actuated in a predetermined sequence from the drum 24.

When the bits are on the upper surface of the designer wheel as illustrated, they are arranged to be depressed when they are not required to elevate a needle. A bit in the depressed position is illustrated in Figure 5, in which figure all the feet 27 are shown in the depressed position although it will be understood that during a large portion of the patterning, only one or two of the feet will be thus depressed. The relative position of a needle with respect to the bits is illustrated at 48 in Figure 5. When the bits are not depressed, they are in a position to engage the butts of the needles or needle jacks and to raise them to the required patterning height. The bits are normally maintained in their raised positions by means of spring fingers 49 secured to and projecting radially from the ring 13. With each bit 14, there is associated one spring finger, such as 49, which presses on the underside of the bit as shown. In order that during the raising of the needle there shall be no danger of the resistance of a spring, such as 49, becoming flexed, a dividing cam 50 is provided. The cam 50 extends from a bracket 51 fixed to the cam-box so that the designer wheel 10

will rotate relatively to the cam 50. As the bits approach the dividing cam, a tapered portion or extremity thereof serves to engage within the jaw formed at the outer ends of the bits if they have not been depressed by the feet 27. On the other hand, if they have been depressed, the upper member of the jaw or fork engages the underside of the cam 50. These two positions are clearly shown in Figure 6, the left-hand bit representing one that has not been depressed and the right-hand bit representing one that has been depressed. The dividing cam 50 serves to operate on the bits 14, and in the cam-box there is another dividing cam 52 for the needles so that the butts of the needles that have been raised by the bits 14 will ride over the cam 52, whereas the butts of those needles of which the associated bits have been depressed, will be directed to the underside of the cam 52.

The latter, therefore, completes the upward or raised movement of those needles which are to be raised to a patterning height, and following the selection of the needles by the cam 52, another lifting cam 53 serves to raise all the needles to a knitting height to take in a ground thread. The cam 52 serves to raise the selected needles to take in a plating or patterning thread as in the example illustrated. The relative patterning and ground thread feeder positions are indicated at 54 and 55 respectively. The usual stitch cam, such as 56, is provided within the cam-box to cause all the needles to make a stitch after they have passed from the influence of the cam 53. There may be any desired number of designer wheels, such as 10, and sets of cams in the cam-box as may be found necessary or desirable according to the size of the machine and the nature of the fabric to be knitted.

It will be appreciated that the construction is subject to many modifications without departing from the spirit of the invention.

I claim:—

1. The combination of a designer wheel having a plurality of bits each of which is pivotally mounted in the wheel and has a projection for engagement by a selector element, said projections differing as between one bit and another in their positions in the lengths of the bits, and all said projections being of the same height, and selector elements allocated respectively to different projections and each capable of operatively engaging an appropriate one of said projections for the purpose described.

2. The combination of a designer wheel having a plurality of bits each pivotally mounted in the wheel, selector elements each capable of operatively engaging with and swinging appropriate bits about their pivots for the purpose described, and a bit-dividing

cam which is so disposed as operatively to engage said bits after they have been influenced by the selector elements and which serves to guide and retain selected and unselected bits in their relative positions while they are operative for design control.

3. The combination of a designer wheel having a plurality of bits each of which is pivotally mounted in the wheel and has a fork at its outer extremity, selector elements each capable of operatively engaging with and swinging appropriate bits about their pivots for the purpose described, and a bit-dividing cam which is so disposed as operatively to engage said bits after they have been influenced by the selector elements, the forked extremities of the bits being so shaped that each fork can alternatively embrace the dividing cam to be guided thereby or it can ride over the surface of the cam according to the position into which the bit is moved by a selector element.

4. The combination of a designer wheel having a plurality of bits each pivotally mounted in the wheel, and selector elements each capable of operatively engaging with and swinging appropriate bits about their pivots, for the purpose described, each selector element comprising a pivotally-mounted lever movable towards and away from the bit in a direction to swing the latter about its pivotal axis.

5. The combination of a designer wheel having a plurality of bits each pivotally mounted in the wheel and selector elements each capable of operatively engaging with and swinging appropriate bits about their pivots for the purpose described, each said selector element comprising a pivotally-mounted lever and a separate plunger operatively connecting said lever with appropriate bits and movable in a direction to swing said bits on their pivots, and a slotted guide for all the said plungers.

45 6. The combination of a designer wheel having a plurality of bits each pivotally mounted in the wheel, and selector elements each capable of operatively engaging with and swinging appropriate bits about their pivots for the purpose described, each selector element comprising a pivotally-mounted bell-crank, one arm of which can be operatively engaged with the said bit, and the other arm is for engagement with selector-actuating means.

7. The combination of a designer wheel having a plurality of bits each pivotally mounted in the wheel, and selector elements each capable of operatively engaging with and swinging appropriate bits about their pivots for the purpose described, each selector element comprising a bell-crank, a separate plunger engaged with one arm of the bell-crank and serving operatively to con-

nect the latter with appropriate bits, and a slotted guide for all the said plungers.

8. The combination of a designer wheel having a plurality of bits each pivotally mounted in the wheel, selector elements each capable of operatively engaging with and swinging appropriate bits about their pivots for the purpose described, each selector element comprising a pivotally-mounted bell-crank and a separate plunger engaged by one arm of the bell-crank and operatively connecting it with appropriate bits, and selective actuating means for engaging the other arm of said bell-crank.

9. The combination of a designer wheel having a plurality of bits each pivotally mounted in the wheel, selector elements each capable of operatively engaging with and swinging appropriate bits about their pivots for the purpose described, each selector element comprising a pivotally-mounted bell-crank and a separate plunger engaged by one arm of the bell-crank and operatively connecting it with appropriate bits, and a rotary device bearing selective actuating means for engaging the other arm of said bell-crank.

10. The combination of a designer wheel having a plurality of bits each pivotally mounted in the wheel, projections on said bits which differ, as between one bit and another, in their positions in the lengths of the bits so that they lie in one or another of a plurality of annular zones coaxial with the wheel, selector elements allocated one to each of said zones, each selector element being capable of operatively engaging with and swinging about their pivots the bits whose projections are in the zone of the selector.

11. The combination of a designer-wheel having a plurality of bits each pivotally mounted in the wheel, selector elements each capable of operatively engaging with and swinging appropriate bits about their pivots for the purpose described and a bit-dividing cam which is so disposed as operatively to engage the bits to raise them to a full height whereas the selector elements serve only to assist in raising the bits to a height sufficient to be engaged by the dividing-cam but not to a height sufficient to obtain the requisite selection.

12. The combination of a designer-wheel having a plurality of bits each of which is pivotally mounted in the wheel and has a projection for engagement by a selector element, said projections differing as between one bit and another in their positions in the lengths of the bits, and selector elements which are allocated respectively to different projections, which are arranged side by side in a row substantially parallel with the length of a bit when co-operating therewith and which are each capable of operatively engaging appropriate projections in order

to move the bits in a direction perpendicular to the length of the said row.

13. For a knitting machine having needles controlled by movable bits in a designer-wheel, the combination of a designer-wheel having a plurality of bits, each of which is pivotally mounted in the wheel, and has a projection for engagement by a selector element, said projections differing as between one bit and another in their positions in the lengths of the bit, cooperating selector-elements therefor, each of which is movable into and out from a position in which it can operatively engage appropriate projections on the bits and swing the latter about their pivots for the purpose described, the bits being so mounted in the wheel that those portions of them which are operative to move the needles are movable by the selector-elements in the direction of the lengths of the needles.

14. The combination of a designer-wheel having a plurality of bits, each of which is pivotally mounted in the wheel and has at least one projection for engagement by a selector element, said projections differing as between one bit and another in their positions in the lengths of the bits, and said bits being pivotally mounted in the wheel in such manner that they will move about their pivots in the general direction of the lengths of the needles which they are to control, and selector elements allocated respectively to the different projections and each capable of operatively engaging appropriate projections, for the purpose described.

15. The combination of a designer-wheel having a plurality of bits each of which is pivotally mounted in the wheel and has a portion thereof specially formed for engagement by a selector element, said specially formed portions differing as between one bit and another in their positions in the lengths of the bits, and said bits being each so mounted in the wheel that their swinging movements about their pivots will be in the general direction of the lengths of the needles with which they are to cooperate, and selector elements allocated respectively to different ones of said portions and each capable of engaging its appropriate portion, for the purpose described.

16. The combination of a designer-wheel having a plurality of bits each of which is pivotally mounted in the wheel, and has a portion thereof specially formed for engagement by a selector element, said specially formed portions differing as between one bit and another in their positions in the lengths of the said bits, resilient means tending normally to retain the bits at one limit of their pivotal movement, and selector elements allocated respectively to the different ones of said portions and each capable of operative-

ly engaging with and swinging appropriate bits about their pivots against the action of the resilient means.

In testimony whereof I affix my signature.

HENRY HAROLD HOLMES.
